UNITED STATES PATENT OFFICE.

ANDREW A. MACDONALD, OF LENOX, MASSACHUSETTS.

DESIGN FOR A BOX.

SPECIFICATION forming part of Design No. 26,298, dated November 17, 1896.

Application filed September 30, 1896. Serial No. 607,504. Term of patent 7 years.

To all whom it may concern:

Be it known that I, ANDREW A. MACDONALD, a subject of the Queen of Great Britain, residing at Lenox, in the county of Berkshire 5 and State of Massachusetts, have invented or produced a new Design for a Flower-Shipping Box, of which the following is a specification.

This box is especially for shipping violets and similar small flowers.

10 The leading feature in this design for a box consists in a rectangular partition with a circular opening and an adjacent hollow downwardly-projecting cone.

In the drawings, Figure 1 is a vertical section, and Fig. 2 is a plan view, of the box.

The partition *a* is rectangular with a central circular opening, and the hollow cone *b* is below this opening, and these are within the lower part *c* of the box, and *d* is the cover.

I claim—

20 The design for a flower-shipping box, substantially as described and shown.

Signed by me this 10th day of September, 1896.

ANDREW A. MACDONALD.
